UNITED STATES PATENT OFFICE.

ALBERT C. McDONALD, OF KALAMAZOO, MICHIGAN.

DANDY-ROLL.

1,071,329.

Specification of Letters Patent.

Patented Aug. 26, 1913.

Application filed April 4, 1912. Serial No. 688,495.

To all whom it may concern:

Be it known that I, ALBERT C. McDONALD, a citizen of the United States, residing at Kalamazoo, in the county of Kalamazoo and State of Michigan, have invented certain new and useful Improvements in Dandy-Rolls, of which the following is a specification.

This invention relates to new and useful improvements in dandy rolls and is designed particularly to construct a device of this nature which will increase the efficiency of devices of this type. Dandy rolls are used upon the wet end of the paper machine and are designed to finish the top side of the paper and also water mark the same. As these rolls operate upon the paper while the same is in a soft or pliable condition, they will naturally gather or accumulate a quantity of foam water, and stock, which must be discharged by some method if the roll is to operate properly. In the rolls heretofore used, an attempt has been made to produce such a discharge preferably at the ends of the roll, but it has been found that these rolls have not been very successful, and in the majority of instances the rolls have become dammed and fail to operate as desired. The present invention is designed to overcome this objectionable feature in the rolls now in use by providing a means whereby a continual discharge may be had at the end of the roll, keeping the latter clear of accumulated foam and water and thereby preventing the rolls from damming.

With the above and other objects in view, this invention consists in the construction, combination, and arrangement of parts, all as will be hereinafter more fully described, illustrated and claimed, wherein:

Figure 1 is a diametrical view illustrating the shell of the roll flattened out. Fig. 2 is a side elevation of the dandy roll illustrating the various sections thereof, broken away for the purposes of illustration.

Reference being had more particularly to the drawing, 10 indicates a metal ring located at each end of the roll having a number, preferably 4, of radially extending arms 11 located upon the interior thereof, whereby a stub shaft 12 is secured to each ring 10 for the mounting of the roll. A plurality of parallel longitudinal ribs or wires 13 are interposed between the heads

or rings 10, said ribs or wires 13 constituting the inner surface or base of the shell of the roll. A pair of parallel wires 14, spaced substantially one-half inch apart, are wound spirally above the ribs or wires 13 from one plate 10 continuously to the opposite plate 10, forming a channel upon the exterior of said ribs or wires 13, of about one-half inch in width. This channel is particularly constructed to conduct the foam, stock and water gathered by the dandy roll to the ends thereof, in order that the same may discharge, and the utility of the roll be in no way impaired thereby. In order to brace these channel forming wires 14, and to prevent any longitudinal movement thereof, a wire 15 is interposed between the wires of each set. This wire 15 is staggeredly arranged between the adjacent wires 14 and is secured to said wires by a soldering or other suitable means at equidistant intervals, as is clearly illustrated in the drawing. From this construction it will readily be seen that the wires 14, forming in combination a conducting channel, are prevented from any movement whatsoever upon the wires or ribs 13, and are retained by the wire 15 in a fixed position. The entire structure is wound with a spring brass wire 16 which extends throughout the entire length of the roll and completely covers the entire mechanism. An outer cover or brass wire gauze or cloth 17 incases the entire shell or roll and constitutes the bearing surface thereof.

By the foregoing construction it will be seen that as the roll operates upon the wet paper, the foam, stock, and water will pass through the brass wire, cloth or gauze 17 through the winding wire 16 and into the interior of the shell. The water, foam, etc., will naturally, by gravity, be retained at the lower terminal of the vertical diameter of the roll, and thus will positively contact with the channels formed by the wires 14. The rotation of the roll will therefore carry the foam, stock, etc., to one end of the roll, where it will be discharged.

Having thus fully described my invention, what I claim as new and desire to secure by U. S. Letters Patent, is:

In a dandy roll, the combination with a pair of spaced rings, of a series of longitudinally extending parallel wires or ribs in-

terposed between said rings, a pair of continuous spaced wires spirally encircling said ribs or wires, constituting in combination, a channel, and a staggered wire arranged 5 between said spirally arranged wires, for retaining same in a fixed position.

In testimony whereof I affix my signature in presence of two witnesses.

ALBERT C. McDONALD.
